Primary Examiner — Joseph Kukella*Assistant Examiner* — Arva P Adams(57) **CLAIM**

The ornamental design for a closure for smoking cocktails, as shown and described.

DESCRIPTION

1. Closure for smoking cocktails
- 1.1 : Top view in the closed position
- 1.2 : Top view in the open position
- 1.3 : Front
- 1.4 : Back
- 1.5 : Left
- 1.6 : Right
- 1.7 : Bottom
- 1.8 : Perspective view from above
- 1.9 : Perspective view from below

(Continued)

The closure can be placed on a glass and smoke can be introduced through the central hole, which is closable by the sliding disc.
